(57) **CLAIM**

The ornamental design for a control for vehicles as shown and described.

DESCRIPTION

FIG. 1 is a front view of a first embodiment of a control for vehicles of our present design;

FIG. 2 is a rear view thereof;

FIG. 3 is a left side view thereof;

FIG. 4 is a right side view thereof;

FIG. 5 is a top front perspective view thereof;

FIG. 6 is a rear bottom perspective view thereof;

FIG. 7 is a front right perspective view thereof;

FIG. 8 is a front view of a second embodiment of a control for vehicles of our present design;

FIG. 9 is a rear view thereof;

FIG. 10 is a right side view thereof;

FIG. 11 is a left side view thereof;

FIG. 12 is a top front perspective view thereof;

FIG. 13 is a rear bottom perspective view thereof; and,

FIG. 14 is a front right perspective view thereof.

The broken lines depicting a boundary around the de-emphasized elements, and the de-emphasized elements within, illustrate portions of the control for vehicles which form no part of the claimed design.

1 Claim, 14 Drawing Sheets
